United States Patent Office

Des. 216,689
Patented Mar. 3, 1970

216,689

HEADREST

Kimiyoshi Isogai, 1830 Sugamo 7-chome,
Toshima-ku, Tokyo, Japan

Filed Nov. 14, 1968, Ser. No. 14,459

Term of patent 14 years

Int. Cl. D6—01

U.S. Cl. D15—8

Fig. 1

Fig. 4

Fig. 2

Fig. 5

Fig. 3

FIG. 1 is a top plan view of a headrest, showing my new design;

FIG. 2 is a front elevational view;

FIG. 3 is a back elevational view;

FIG. 4 is a bottom plan view; and

FIG. 5 is a left end elevational view, the right end elevational view being substantially a mirror image thereof.

I claim:

The ornamental design for a headrest, substantially as shown and described.
